UNITED STATES PATENT OFFICE.

HUGH BOYD, OF DOWNEY, IOWA, ASSIGNOR TO ROBERT W. SMITH, OF DOWNEY, IOWA.

DUMPING END-GATE.

SPECIFICATION forming part of Letters Patent No. 723,815, dated March 31, 1903.

Application filed August 23, 1902. Serial No. 120,818. (No model.)

To all whom it may concern:

Be it known that I, HUGH BOYD, a citizen of the United States, residing at Downey, in the county of Cedar and State of Iowa, have 5 invented a new and useful Dumping End-Gate, of which the following is a specification.

My invention consists in an improved end-gate for wagons, and is especially adapted for use in grain-wagons.

10 The object of my invention is to produce a gate which will facilitate both loading and unloading, which will prevent grain or the like from falling from the rear of the wagon during the operation of loading, and which 15 can be easily raised and lowered.

Another object of my improvement is to produce an end-gate which will serve as an extension of the wagon-bed, thus permitting the wagon to be backed nearer to a bin or 20 other receptacle from which grain is being taken.

In the accompanying drawings, Figure 1 is 25 a perspective view of the rear end of a wagon with my improved end-gate in position. Fig. 1^a is an enlarged detail view hereinafter explained. Fig. 2 is a perspective view showing a section of my gate raised for unloading. Fig. 3 is a perspective view showing the 30 gate in position for loading. Figs. 4 and 5 are detail views. Fig. 6 is a detail of a holding-plate.

In the construction of my improvement I attach to the body A of a wagon or cart a bracket A', having at its rear end a perforated lug A², one of the brackets being placed 35 adjacent each upper rear corner of the wagon-bed, and below each bracket is a turn-button A³, which is shown in detail in Fig. 6.

The end-gate proper consists of a frame 40 having the side pieces B and the cross-pieces B', B², and B³, and lengthwise of this frame are the boards B⁴ B⁵. Across the upper ends 45 of the boards B⁵ extends the cross-piece B⁶, which is hinged at B⁷ to the cross-piece B². The cross-pieces B' B² are secured to the side 50 pieces B and the boards B⁴, the piece B² extending beyond the side pieces. The piece B³ extends also slightly beyond the sides B, but is secured directly only to the boards B⁵. 55 At its lower end this gate-frame is pivoted to the wagon-bed at C. Near the ends of the

cross-piece B³ are secured metal strips D, formed with an offset, the shoulder produced thereby resting against the upper edge of the cross-piece. Turn-buttons D' are secured to 55 the side members adjacent the strips D and are adapted to be bent down and rest on the offset.

To hold the gate in position, I provide a metal member E, bent in the form of a rectangular frame, one of the sides being bent back upon itself at E' to form a locking-loop and adapted to be engaged by the turn-button A³. The member E passes through the lugs on the brackets A' and thence through 65 apertures produced in the cross-piece B², and to avoid wear on same the apertures are surrounded by metal rings E², which slide on the bar E as the gate is raised and lowered.

In Fig. 4 I have shown a modification of the 70 member E, in which it is composed of two U-shaped members E⁴ E⁵, having interlocking eyes E⁶ and the locking-loop at E'.

The operation of my device will be readily understood. When raised into a vertical position and the button A³ turned down over the loop E' and the button D' is turned over the upper end on the strip D, the gate is securely held in position to close the end of the wagon-body. To unload, it is not necessary to let 75 down the entire gate, for by turning the button D' up the lower half of the end-gate can be lifted, as clearly shown in Fig. 2. Any convenient means of securing this swinging section in a raised position may be employed. 80 When loading, or when for any other reason it is desired to have the entire gate down, the button A³ is turned up, the member E can then be lifted from it, and the entire end piece swung into the position shown in Fig. 3. It 85 is also obvious that while in this position the lower section can also be unfastened and swung down.

The advantage of my end-gate in loading grain will be evident, for with the gate in the 90 position shown in Fig. 3 it forms a rearward extension of the wagon, and the wagon can be backed so as to bring this extension over the grain-bin, and when grain is thrown into the wagon from the rear the gate will prevent 95 any of it from rolling from the rear of the wagon to the ground. It will also be noted

that no cleats or slots are provided for the parts to slide in, and which would, if such were used, be continually filling up with grain and require cleaning out in order to permit 5 the gate to be operated. My gate can be placed in its closed position, as shown in Fig. 1, with the wagon loaded as readily as with it emptied.

It is obvious that a number of slight modifications and changes can be made in the construction of my device without departing from the spirit of my invention. For example, a holding-plate C', having two vertical sides C² at right angles to each other, may be 15 secured by a suitable bolt to the body of the wagon and be adapted to receive the lower rear edge of the side pieces B, as shown in Fig. 1.

Having thus fully described my invention, 20 what I claim as new, and desire to secure by Letters Patent, is—

1. An end-gate comprising standards pivoted at their lower ends to the body of the wagon, cross-pieces connecting the standards, 25 one of said cross-pieces being perforated ad-

jacent its ends, hooks secured to the sides of the wagon, a swinging section hinged to one of the cross-pieces, and metal locking members bent on one side to form locking-loops, said locking members passing through the 30 perforations in the cross-piece, the loops being adapted to engage the hooks.

2. In an end-gate, the combination with a main section, a half-section hinged to said main section, a cross-piece having ends extending beyond the sides of the main section said cross-piece being perforated adjacent its ends, brackets having ends terminating in perforated lugs secured to the wagon-body below the brackets, and metal frames having 35 one member passed through the lugs of the brackets and the apertures of the cross-pieces, and having their other member bent to form a locking-loop adapted for engagement with the turn-buttons substantially as specified. 40 45

HUGH BOYD.
